UNITED STATES PATENT OFFICE

2,063,415

IRONING MACHINE

Robert J. Waterworth, Sidney, Ohio, assignor to
 Prima Manufacturing Company, Inc., Sidney,
 Ohio, a corporation of Ohio

Application April 2, 1934, Serial No. 718,622

5 Claims. (Cl. 35—60)

This invention relates to improvements in ironing machines, and has for its object to provide an ironing machine of which the table is formed of a pressed steel top, legs and braces, 5 and has a die-cast housing which carries the driving mechanism, the clutch control and the tubes for the roll and the ironing shoe.

It is an object of this invention to provide an ironing machine in which the roll may be used 10 either for ironing or pressing purposes by the operation of a suitable instrumentality.

It is an object to provide, in connection with the ironing machine roll, a locking knob by 15 which the roll is attached to the roll tube.

It is also an object of this invention to provide means for connecting the roll and the power for operating the roll in such a manner 20 that the roll may continue to rotate until the shoe is a considerable distance from the roll, whereby the goods being ironed may be manipulated to remove creases, or may be moved from one end of the roll to the other.

It is also an object of the invention to provide a support for the shoe that will permit its 25 ready and uniform cooperation with the roll for ironing purposes.

It is also an object to provide a foot-operated lever for operating a clutch to cause the roll to 30 rotate and also to bring the shoe into engagement with the roll, this lever being so operated by the foot of the operator that the movement of the foot is coordinated with the movements of the other parts of the body in ironing.

It is a further object to provide an improved 35 and efficient lubricating system for lubricating the worm shaft which operates the roll.

It is an object to provide an improved connection between the heating elements and the wires leading to the shoe.

40 These and other objects and advantages will appear from the following description taken in connection with the drawings.

Referring to the drawings:

Figure 1 is a front elevation of the ironing 45 machine with certain parts broken away to show the internal operating parts.

Figure 2 is an elevation of the gear housing with the cover removed therefrom.

50 Figure 3 is a vertical section along an irregular line through the shaft centers and the housing showing the means by which the roll is supported and operated, and the means by which the shoe is supported.

55 Figure 4 is an end elevation of the complete

machine with the shoe in engagement with the roll.

Figure 5 is a back view of the shoe structure.

Figure 6 is a section on the line 6—6 of Figure 5.

Figure 7 is a view showing the means by which the wires are attached to the heating elements.

Figures 8, 9, 10, and 11 show progressive steps 10 in the building up of the insulating protection on the heating elements together with the wire protectors.

Figure 11a is a view showing the manner in 15 which the cable conduit is connected to the shoe structure.

Figure 12 is an inside view of the cover for the gear housing.

Figure 13 is a section on the line 13—13 of Figure 12.

Figure 14 shows the worm shaft and the worm 20 shaft bearing.

Figure 15 shows the worm shaft removed from the bearing.

Figure 16 shows the worm shaft and the 25 worm shaft bearing with the bearing casing in section.

Figure 17 is a vertical section through the outer end of the ironing roll and its locking mechanism.

The instrumentalities for supporting the ironing 30 parts (Figure 1) consist of a table having a top 1 and end flanges 2, to which are attached legs 3 by means of bolts 4. The legs are braced by means of end braces 5 and a rear brace 6. Supported beneath one end of the table is a motor 7, held in spaced relationship near the table by means of spacers 8 through which screws 9 pass for supporting the motor on the table.

The motor shaft is provided with a motor 40 coupling 10 by which the motor is operatively connected to a worm shaft for transmitting power to the moving parts of the ironing machine.

In one corner and on top of the table is a name-plate 12, which has therein a switch 13 for cutting the current on and off of the heating unit.

The motor is provided with a lead cord 11, which has on its end a plug for connecting the cord to a suitable socket in the wall, or some other place. Extending from the switch are wires 14 for conducting current to the heating unit. These wires extend through a flexible conduit 15, which has one end suitably attached to the back of the shoe.

Supported on one end of the table top is a gear

housing 16, which is die-cast and carries the operating gears, the clutch and supports the tubes for the roll and the ironing shoe. This gear housing has a base 17, which is attached to the top of the table by means of bolts 18. Extending upwardly through the base is a worm shaft 19 connected at one end to the motor coupling 10 and supported at its other end by a bracket.

10 The worm shaft (Figure 2) is located in a bearing 20, which is supported in a bearing casing 21 integral with and extending upwardly from the gear housing floor 22. Immediately beneath the bearing 20 and around the worm shaft are leather washers 23, which have beneath them a retaining washer 24. The bearing 20 is held within the casing 21 by means of a set screw 25. Around the shaft 19 and resting upon the bearing 20 is a thrust washer 26, which 15 has above it a worm shaft collar 27 attached to the shaft by means of a pin 28. The worm of the shaft is indicated by the numeral 29. The upper end of the worm shaft is supported by means of an arm 30 which extends from 20 the rear of the housing toward the open side thereof. The worm 29 engages a worm gear 31 on the shaft 32 and has integral therewith a pinion 33 which meshes with a gear 34. The shaft 32 is supported by means of a boss in one 25 side of the gear housing.

The gear 34 is loosely mounted upon a drive or roll shaft 35 and is held against longitudinal movement on the shaft by means of a cotter pin 36. Extending rearwardly from the gear 30 housing and adjacent the top thereof (Figure 3) is a cone-shaped projection 37, which has therein a cylindrical sleeve 38. This sleeve extends through a back 38a of the housing and has attached thereto a roll tube 39. Within this roll tube 39 is a collar 40 secured thereto by a pin 41. This collar is located around the roll shaft and between the roll shaft and the roll tube, and serves as a retainer for a bearing 42 located between the roll shaft and the roll tube.

45 Adjacent the bearing are felt washers 43. The roll shaft has thereon a clutch member 44 adapted to move longitudinally thereof and to rotate therewith through the instrumentality of a key 45. The clutch 44 is adapted to engage a clutch 46 on the hub part of the gear 34 so that when these clutch elements are in engagement the rotation of the gear 34 will cause the shaft 35 to rotate. The clutch 44 is provided with a groove 47 to receive the yoke end 58 of 50 a lever 48 pivoted at the point 49 on the floor of the housing. This arm is acted upon by means of a spring 51 tending to hold the clutch members in engagement.

The roll shaft 35 and the roll tube 39 have 55 mounted thereon a roll 52 (Figure 1), which is hollow and cylindrical and has at each end a cup-shaped end member 53, each of which has an outwardly extending flange or cylindrical part 54 to which a tubular member 55 is attached. Extending inwardly from each end member and in a direction opposite that of the flange 54 thereof, is an inner tubular member 56 adapted to rotate around the roll tube and supported on the roll tube by means of roller bearings 57.

70 The roll shaft 35 extends longitudinally through the roll and is attached at its free end to the roll by means of a roll locking knob 58. This locking knob 58 is attached to the end of the roll shaft 35 by means of a set screw 59 75 and has an inwardly extending tubular exten-

sion 60 between the shaft and the end of the roll tube remote from the gear housing. The roll locking knob 58 is attached to the end member 53 remote from the gear housing by means of a drive pin 60a. This end member has its 15 tubular member 56 provided with roller bearings 57 between it and the roll tube. The roll shaft is provided with a spiral groove 61 for the purpose of transmitting lubricant from the gear housing to the end of the roll tube remote 10 from the housing. Around the roll 52 are layers of material for building up the circumferential part of the roll. There is, first, a pad 62 about which there is an under cover 63 and an outer cover 64.

15 Located in the gear housing and adjacent the floor thereof (Figures 2 and 3) is an inwardly projecting boss 65 having a bore which supports a control shaft tube 67, having therein a control shaft 66. Around the shaft and between the 20 shaft and the control tube is an oil seal packing ring 68 of any suitable and conventional type. Secured to the outer end of the control shaft 66, as by the pin 69a, is the hub of a cam lever 69 (Figures 2 and 3). On the free 25 end of the arm 69 is mounted a bolt 70, which has thereon a head for engagement with a cam surface 71 on the lever 48. The lever has thereon a projection 72 so arranged that the head of the bolt 70 cannot pass from the lever in its 30 movement toward the top wall of the gear housing.

One end of the control shaft 66 is supported by the structure just described, while its other end is supported by means of a bracket 73 35 (Figure 1) suitably attached to the top of the table. On the end of the control shaft beyond the bracket 73 and held thereon by means of set screws 75 and a collar 76 is the hub 74 of a downwardly extending arm 77, which is longitudinally grooved (Figure 4) to receive one end 40 of the pressure lever 78, attached thereto by means of a bolt 79.

On the lower end of the pressure lever is a 45 foot rest 80, which has extending upwardly therefrom two spaced arms 81 by which the foot rest is attached to the lower end of the lever by a bolt 82. This foot rest may be adjusted with relation to the pressure lever so it may extend either to the righthand side or to 50 the lefthand side of the pressure lever. To the arm 77 (Figure 4) is attached one end of a spring 83 which tends to hold the foot rest in its forward position. Extending upwardly from the hub 74 is an arm 84 which has attached 55 thereto one end of each of two springs, one a pressure spring 85 and a second pressure spring 86 (Figure 4).

The hub 74 is provided with a socket 74a arranged to receive a plunger 84a, which is reciprocably mounted in a bore in the bracket 73, urged toward the socket 74a by a spring 84b and operated by means of a knob 84c (Figure 1). This plunger 84a projects beyond the lug supporting it and in the path of the arm 84 for holding this arm 84 in position with relation to the roll. By withdrawing the plunger 84a from the socket 74a the arm 84 may be moved backward, carrying with it the shoe so as to provide a wider space between the shoe and the roll. The second spring 86 is for the purpose of holding the shoe in proper position when the shoe is withdrawn from engagement with the ironing roll.

The shoe structure (Figure 6) includes a cover 87, which has on its rear face a pair of lugs 88 supporting a hinge pin 89 to which the curled or spiral end 89 of the pressure spring 85 is attached (Figure 4). By means of this pressure spring support for the ironing shoe the shoe will readily adapt itself to the position of the roll so that all parts of the shoe will contact equally with the parts of the roll. By this support the shoe may yield to the nature of the material operated upon. If some parts of the material be thick, that part of the shoe will be spaced a greater distance from the roll without interfering with the other parts of the shoe 15 properly contacting the roll.

The cover has each end bent in, somewhat as the ends of a trough, to protect the insulating and the heating elements between the cover and the shoe 91 (Figure 6). The shoe is provided with laterally extending flanges 92 which project beyond the lateral edges of the cover. Between the shoe and the cover are heating elements 93 (Figure 7) protected by means of suitable insulation. The heating elements 93 are embedded in a plate of some suitable formation, which has over it a sheet of asbestos 94 (Figure 8). Over this sheet of asbestos is a terminal protector pad 101 of any suitable heat-resisting insulating material, such as mica, and superimposed upon this is a pressure plate 95. The asbestos sheet, the heating elements and the pressure plate are held in proper position with relation to the shoe by means of bolts 96 with nuts 97 thereon.

On the outside of the pressure plate is an asbestos sheet 98, which is broader than the asbestos sheet 94 and is adapted to cover a larger area of the inside surface of the shoe. Over these nuts and the asbestos sheet 98 is placed the cover, which is provided with holes to receive the bolts 96. On these bolts, without the cover, are lock washers 99 and nuts 100. These nuts together with the bolts hold the assembled shoe structure together.

The terminals of the wires 14 within the shoe structure (Figure 5) are supported by the mica terminal protector pad 101, which is merely a pad for the purpose of protecting the wires 14 and adjacent parts at the end of the asbestos sheet 94. The end of the conduit through which these wires extend projects through a suitable hole therefor in the back, and is flared at 102 so that this conduit is securely held with one end attached to the cover. The wires are connected to the heating elements by means of strips 103 (Figure 7). One of these strips passes through a slit 104 and is attached to the heating element, while the other strip 103 passes through a slit 105 and is attached to the other end of the heating element.

The gear housing is provided with a cover 106 (Figures 12 and 13) which has a bushing 107 for supporting a cam shaft 108. This cam shaft has on one end, on the outside of the cover, a knob 109 attached thereto by means of a screw 110. On the other end of this cam shaft is a pressure cam 111 adapted to engage the lever 48 for holding the clutch members out of engagement with each other so that the ironing operation may be carried on without the roll rotating. In other words, the ironer may be used as a presser. This pressure cam is supported on a disc 112 which has extending therefrom a sleeve 113 attached to the cam shaft by means of a pin 114. The disc, cam and

sleeve are preferably integral. The inside of the cover is also provided with a lug and socket 115 for supporting one end of the shaft 32.

The gear housing serves to contain a lubricant for lubricating the moving parts therein, and in order that the worm shaft and its bearing may be properly lubricated the bearing has a slot 116 (Figure 16) extending from the top of the bearing to a point near the lower end thereof, where it terminates in a drilled hole 10 117 leading through the bearing to the shaft. The shaft is provided with a spiral groove 118 which on rotation of the shaft tends to move the lubricant from the lower end of the bearing toward a hole 119 at the upper end thereof. At 15 the lower end of the bearing there is a lubricant seal 119, which prevents the lubricant from passing downwardly from the bearing toward the motor coupling.

The backward movement of the lever 78 will 20 bring the shoe into engagement with the roll and at the same time rock the arm 69 to release the lever 48 so that the spring 51 will cause the clutch elements to interengage, whereby the roll will be caused to rotate. A release of the 25 lever 78 will cause the shoe to move from the roll and the clutch elements to disengage. But the clutch elements do not disengage until the shoe has moved some distance from the roll, whereby clothes may be manipulated between the roll and the shoe while the roll is rotating to remove folds and creases, or the clothes may be moved to various parts of the roll.

If it be desirable to use the machine for pressing purposes, the cam 111 may, by operating the knob 109, be brought to bear upon the lever 48 to disengage the clutch elements against the action of the spring 51, which tends to hold the clutch elements in engagement.

It will be understood that I desire to comprehend within my invention such modifications as come within the spirit and scope of my invention as set forth in the appended claims.

Having thus fully described my invention, what I claim as new and desire to secure by Letters Patent, is:

1. In an ironing machine, an ironing shoe, a movable member having attached thereto a pair of contiguous pressure springs arranged with one spring adjoining the other, and means 50 for pivotally attaching the shoe to one spring, said other spring being positioned in such proximity to said pivoted spring that the shoe will be partly and yieldingly supported by the other spring.

2. In an ironing machine, in combination with a roll, an ironing shoe adapted to engage and cooperate with the roll for ironing and pressing purposes, and a lever having thereon a pair of curled springs, the shoe being pivoted to one end 60 of one spring and engaged by the other spring, whereby on proper movement of the lever the shoe will be pressed against the roll.

3. In an ironing machine, in combination with a roll, an ironing shoe adapted to engage and 65 cooperate with the roll for ironing and pressing purposes, and a lever having attached to one end one end of each of a pair of curled springs, said shoe being pivotally attached to the other end of one spring and engaging the other end 70 of the other spring, whereby on proper movement of the lever the shoe will be pressed against the roll.

4. In an ironing machine, a frame, a roll mounted for rotation on the frame rearwardly 75

of said roll, a foot lever pivotally mounted on the frame at a point intermediate its ends, a pair of curled plate springs on the upper end of the foot lever above said pivotal mounting, and an ironing shoe pivoted to one of the curled springs and engaged by the other curled spring, said foot lever being adapted when its lower end is pushed rearwardly to press the shoe with a thrust thereagainst proportional to the pressure exerted by the operator.

5. In an ironing machine, a frame, a roll mounted for rotation on the frame, a vertically directed foot lever pivotally mounted at a point intermediate its ends on the frame, a pair of curled plate springs on the foot lever, and an ironing shoe pivoted to one of the curled springs and engaged by the other curled spring and adapted to be pressed against the roll when the foot lever is moved.

ROBERT J. WATERWORTH. 10
